UNITED STATES PATENT OFFICE.

FRANK A. NYE, OF PHILADELPHIA, PENNSYLVANIA, ASSIGNOR TO NYE & TRENDICK, OF SAME PLACE.

CIRCULAR-KNITTING MACHINE.

SPECIFICATION forming part of Letters Patent No. 556,514, dated March 17, 1896.

Application filed June 11, 1894. Serial No. 514,213. (No model.)

To all whom it may concern:

Be it known that I, FRANK A. NYE, of Philadelphia, county of Philadelphia, and State of Pennsylvania, have invented a new and useful Improvement in Circular-Knitting Machines, 5 of which the following is a specification.

My invention has reference to circular-knitting machines in which dial and cylinder needles co-operate to form a tubular-ribbed 10 fabric.

The invention is directed more particularly to an arrangement of the cams and to a peculiar manner of adjusting the same, having in view the production of a fabric bearing on 15 its surface a polka-dot design, stripe, or a combination of the two.

My invention is shown as applied to the dial of a machine of the form described in the patent to George E. Nye, No. 498,139, dated 20 May 23, 1893, in which two forms of dial-needles are operated by two sets of dial-cams, this arrangement admitting of the production of tuck-strokes by any desired number of the dial-needles and plain stitches by the remainder. 25 The invention is applicable, however, to the cylinder, as distinguished from the dial, provided different sets of cams are used to actuate different forms of needles.

My invention comprises a series of successively-operating cams, adapted to be set in different positions relatively to each other to cause certain of said cams to "knit off" and the remainder to "tuck" and to be reversed as to their relative positions to knit off and tuck alternately, the object being to lay yarn of different colors to the needles in such manner as to cause certain stitches of one color to appear on the surface of the fabric of the prevailing color, the result being a fabric of 30 one color having on its surface a dot or point made up of the stitch of the other color.

The invention also consists in the details of construction and combination of parts hereinafter described and claimed.

45 In the accompanying drawings, Figure 1 is a vertical sectional elevation of the upper portion of a knitting-machine having my invention embodied therein. Fig. 2 is a top plan view of the dial-plate, showing the connections for adjusting the dial-cams. Fig. 3 is a face view of the dial-plate viewed from be-

neath, showing the cams thereon. Fig. 4 is a view showing two forms of needles.

Referring to the drawings, 1 represents a tubular rotary cylinder provided with grooves 55 to receive vertical needles 2, which are reciprocated in the proper manner to form stitches by cams in the cam-cylinder 35, engaging their heels.

4 represents a rotary horizontal plate termed 60 the "dial," which is provided in its upper face with radial grooves containing horizontal needles 5, reciprocated by cams 6 on the under face of a horizontal stationary plate 7, termed the "dial-plate." 65

The dial is provided with needles of two different forms, the difference residing in the lengths of their shanks, or, more properly speaking, in the relative lengths of the shanks between their hooks and heels, as shown in 70 Fig. 4, and they are reciprocated by two series of cams—an inner series for the needles of one form and an outer series for the needles of the other form. The cams are shown in Fig. 3, the needles of one form being projected by the "throw-out" cams 12 to 19 and retracted by the "draw-in" cams 12^a, 13^a, 14^a, 15^a, 16^a, 17^a, 18^a, and 19^a of the inner series, while the other needles are projected by the throw-out cams 12^b, 13^b, 14^b, 15^b, 16^b, 17^b, 18^b, 75 and 19^b and retracted by the draw-in cams 12^c, 13^c, 14^c, 15^c, 16^c, 17^c, 18^c, and 19^c of the outer series.

The machine is shown as provided with an inner and an outer series of eight sets of cams, 80 corresponding to the eight feeds for laying the yarn to the needles, but it will be understood that the number of feeds and corresponding sets of cams may be increased or diminished without departing from the limits of my invention, provided the needles be caused by the relative arrangements and adjustments of the cams, as more fully described herein-after, to cast their stitches at the proper times to cause the color-stitch to appear on the surface of the fabric to form the dot. 85

It will also be understood that the needles of different form are to be arranged in alternating series, the number of needles in each series depending upon the character or style 90 of the work to be produced. Thus if it be desired to produce single-stitch dots in the

prevailing color single needles of appropriate form to be actuated by the inner cams are located between series or groups of needles of the other form adapted to be operated by the 5 outer cams, the distances between such interspersed needles depending upon the distances at which the dots are to be located apart. If the dots are to be extended in a circular direction two or more of the dot-forming needles 10 are placed together, the result being a succession of dots in close relation to each other, from which it will be understood that if a sufficient number of these needles be placed together a circular stripe or line will be 15 formed, the length of which will be determined by the number of needles used.

In applying my invention to a machine of this nature I mount the throw-out cams 12, 13, 14, 15, 16, 17, 18 and 19 of the inner cams 20 so that they may be projected to cause the needles actuated thereby to knit off, or be retracted to cause the needles to tuck as desired, and I further provide for the alternate adjustment or movement of certain of the 25 inner cams to cause the needles to tuck and knit off at the proper times to form a dot or a stripe, as above explained. Each of the throw-out cams of the inner set is pivoted at one end to the dial-plate, the two opposite 30 cams 12 and 16 being provided with vertical upwardly-projecting studs 20 and 21, which extend through slots in the dial-plate to the outside. The stud of the cam 16 is connected by a link 22 to one end of a horizontal lever 35 23, pivoted at its center to the upper side of the dial-plate, the opposite end of the lever being pivoted to a rod 24, which extends laterally and is connected to the upper end of an elbow-lever 25, arranged to operate by a 40 pattern-chain 26 in the usual manner. The stud of the cam 12 is connected by a link 27 to the rod 24 at a point a slight distance from the end of the lever 23. As a result of this arrangement, the cams may be moved out or 45 in by the endwise movement of the rod, the studs moving from one end of the slots to the other, according to the direction in which the rod is moved. The remaining cams of the inner series are connected by links 28 to a ring 50 29, which is suitably mounted in the dial-plate to oscillate to a limited extent with respect to the same. The ring is provided with an upwardly-projecting stud 30, extending through a slot in the dial-plate, which stud is 55 connected by a rod 31 to an elbow-lever 32, arranged to be operated in the customary manner by a pattern-chain 33.

Under the foregoing construction, by properly constructing the pattern-chain, I am enabled 60 to operate the cams 12 and 16 and the remaining cams separately and alternately, and at the proper times to form either a dot or a stripe or plain work, as desired.

The operation of the machine is as follows: 65 If it is desired to form dotted work, the inner cams 12 and 16 are set out to knit off, the remaining inner cams being set to tuck. Of

the inner or throw-out cams of the outer series those (12^b and 16^b) opposite the cams 12 and 16 are set in to tuck. The yarn of the prevailing color is introduced at all the feeds with the exception of those corresponding to cams 12 and 16, at which points yarn of the color to form the dot is fed. The parts being in this position and single needles adapted to be 70 actuated by the inner cams being located at intervals between the needles actuated by the outer cams, a single revolution of the machine will produce the following operation: A needle in passing cam 12 and the three tucking-cams will take, in addition to the color-stitch received at cam 12, three other stitches and on arriving at knitting-off cam 16 will take 75 on a second color-stitch and cast the four stitches it had, the first stitch taken on at 12 80 appearing on the surface of the fabric as a dot. In passing the other three tucking-cams it will take three more stitches and when it arrives at cam 12 again will take another color-stitch and cast the other four, that taken on 85 at 16 appearing on the surface as a dot, in a manner similar to the first stitch. It will of course be understood that each successive needle of the dot-forming needles will be operated in like manner to form a succession of 90 dots in the course. When the machine has completed a single revolution, the pattern-chain will operate to project the throw-out cams 13, 14, 15, 17, 18 and 19 and cause them to knit off and will retract the cams 12 and 16 to cause them to tuck, in which positions the machine will knit plain work—that is, 95 work of one color in contradistinction to dotted work—as long as the rotation of the cylinder and dial is continued.

If it is desired to "stripe" vertically or longitudinally, the cams are left in the first position, (that for the dot,) and the machine being rotated continuously the dots will be 100 formed one beneath another and all close together, so as to join one another and appear as a vertical or longitudinal stripe, the pattern-chain being constructed for this purpose.

The outside tucking-cams before alluded to (12^b and 16^b) are not changed in position, but 105 remain the same either for dot work, stripe work or plain work. The remaining outside cams may, however, be adjusted to knit off or tuck, the essential requirement being that when a dot or stripe is to be formed the outside cams, which correspond in position to the feeds which lay into the needles the dot color, 110 will tuck, it being understood that when the outer needles take the dot color they must cast it off so as to hide it beneath the prevailing color, which they do when tucked, as set forth.

The polka-dot may be made of any size desired, the width depending only on the number of needles used and its length on the 115 number of revolutions of the machine before 120 the cams 12 and 16 are changed.

Having thus described my invention, what I claim is—

In a knitting-machine the combination of the cylinder, its needles, the cam-cylinder, the dial, dial-needles differing in form, the dial-plate, the inner and outer cams thereon comprising movable throw-out cams 12, 13, 14, 15, 16, 17, 18 and 19, a lever pivoted between its ends to the dial-plate, a link connecting cam 16 with one end of the lever, a rod connected to the other end of the lever, a link connecting cam 12 with the rod, means for moving the rod endwise, an oscillating

ring mounted in the dial-plate, links connecting the remaining cams of the inner set to the ring, and means for oscillating the ring.

In testimony whereof I hereunto set my hand this 14th day of May, 1894, in the presence of two attesting witnesses.

FRANK A. NYE.
